UNITED STATES PATENT OFFICE.

GRANT W. SMITH, OF OTTUMWA, IOWA.

ROCK-DRILL.

No. 806,012.

Specification of Letters Patent.

Patented Nov. 28, 1905.

Application filed November 21, 1904. Renewed October 19, 1905. Serial No. 283,499.

To all whom it may concern:

Be it known that I, GRANT W. SMITH, residing at Ottumwa, in the county of Wapello and State of Iowa, have invented certain new and useful Improvements in Rock-Drills, of which the following is a specification.

My invention relates to certain new and useful improvements in rock-drills; and it more particularly seeks to provide a telescopic air-hammer rock-drill of a very simple and durable construction which will readily and effectively serve its intended purposes.

Generically my invention comprises a casing and a suitable support therefor, together with a drilling mechanism proper, which is longitudinally adjustable within said casing and which can be readily and quickly removed from the casing whenever it may be found desirable to do so to replace the drill-tool or for any other purpose. The casing is so arranged that when the tool has been once adjusted the drilling mechanism can be readily and bodily removed from the casing and replaced therein without disturbing the adjustment of the apparatus, so that when the drilling mechanism is replaced the same is in exact alignment with the holder, thereby avoiding the necessity of readjusting the machine. The drilling mechanism proper comprises a tubular section including a pneumatic hammer operable therein and a supplemental tubular section forming an extension and joined to the end of the first tubular section, and means for coupling the two sections together. The adjusting mechanism comprises a plug carried by the second tubular section and which is internally threaded, a cap member for the casing end to which it is detachably secured, a screw co-operating with the cap member and the internally-threaded plug, and means for turning said screw to move the drilling mechanism longitudinally within the casing.

With other objects in view, which will hereinafter be apparent, the invention includes certain novel construction and arrangement of parts, all of which will be first described in detail and then be specifically pointed out in the appended claims, reference being had to the accompanying drawings, in which—

Figure 1 is a perspective view showing my invention applied for use. Fig. 2 is a longitudinal horizontal section thereof. Fig. 3 is a cross-section on the line 3-3 of Fig. 2 looking in the direction of the arrow *a*. Fig. 4 is a similar view on the line 4-4 of Fig. 2 looking in the direction of the arrow *b*. Fig. 5 is

a cross-section on the line 5-5 of Fig. 2 looking in the direction of the arrow *c*. Figs. 6 and 7 are similar views on the lines 6-6 and 7-7, respectively, of Fig. 2 looking in the direction of the arrows *d* and *e*. Fig. 8 is a perspective view of the drilling mechanism proper removed from the shell or casing.

Referring now to the accompanying drawings, in which like characters of reference indicate like parts in all of the figures, 1 designates the casing or shell, which consists of a tubular section having one end 1^a of a slightly-reduced diameter, and the said casing has a longitudinal slot 1^b running from end to end, for a purpose presently explained. The casing 1 passes through and is riveted to a base member 3, which comprises a casting including a base proper, 3^a, and a cylindrical portion 3^b, through which the casing 1 passes and to which it is securely riveted by rivets *x*, as clearly shown in Fig. 5 of the drawings. The base member 3^a is so arranged and constructed as to be bolted to columns or drill-tripods in the usual manner. 3 designates a transverse slot in the cylindrical portion 3^b of the base member 3^a, which alines with the slot 1^b in the casing 1.

Fitted over the end 1^c of the casing 1 is a cap 4, which is preferably formed of cast-steel or other hard material. This cap 4 is formed with a pair of lugs 4^a 4^b and is slotted, as at 4^c, to form a clamp. The lugs 4^a 4^b are apertured to receive a clamping-bolt 5, by means of which the cap 4 is clamped to the casing 1. To prevent the casing end from buckling when the cap is applied, and thereby closing the slot 1^b, I provide the cap 4 with a lug 4^d on its inner periphery, which fits into the slot 1^b and prevents the slot from closing when the cap is secured to the casing. The cap 4 is also formed with a hub 4^e centrally apertured, as at 4^f, to allow the passage of the bearing portion 10^a of the screw 10, which screw 10 is formed with a collar 10^b, which abuts the inner face of the cap 4. The screw 10 is also provided with a squared end 10^c, to which the handle 11 is securely clamped by the bolt 11^a, as shown. The screw 10 from the collar 10^b to its free end is provided with a double thread 10^d for a purpose presently understood, and the said screw 10 projects into the casing 1 in the axial line thereof.

6 designates a supplemental tubular section composed of a piece of extra strong pipe whose end 6^a is internally threaded to receive the threaded portion 9^a of the closure-plug 9.

The plug 9 is provided with an internally-threaded axle-bore 9^b to coöperate with the threaded portion 10^a of the screw 10. At the other end the tubular section 6 is provided with a reduced end 6^b, externally closed at the extreme end by the web 6^c. The portion 6^b is slotted, as at 6^d, so that it can be expanded for a purpose presently explained.

7 designates the shell of the hammer portion of the drilling mechanism, which shell 7 has its end 7^a internally threaded, as at 7^b, to be screwed onto the reduced end 6^b of the tubular section 6.

To tightly screw the sections 6 and 7 together and prevent them becoming unscrewed from one another and to form, as it were, a single tubular member, I provide the ends 6^b of the member 6 with an internally-tapered threaded aperture 6^e to receive a tapered screw wedge-plug 8, having a squared tool-receiving countersunk portion 8^a, whereby it can be screwed into place to expand the end 6^b, and thereby cause it to tightly fit the shell end 7^a.

25 The shell 7 is internally bored to receive a steel casting which forms an inner shell 12. The said shell 12 has its outside surface turned off and is pressed into the shell 7. The inner shell 12 is provided with a plurality of circumferentially-internal grooves 12^a 12^b 12^c 12^d, which form chambers for purposes presently understood. The shell 12 between the grooves 12^c 12^d is formed with a web 12^e, provided with an internal longitudinal bore 12^f of less diameter than the main internal bore of the shell 12 to receive the valve 15 and form a bearing therefor. The valve 15 comprises a cylindrical body portion 15^a of a diameter to pass through the bearing-bore 12^f of the web 12^e 40 and a head 15^b of larger diameter to fit the shell 12. The valve 15 has an internal bore, as at 15^c, and provided with suitable apertures 15^d in the head 15^b and apertures 15^e in the body portion 15^a. The body portion 15^a at its free end is formed with a hardened head portion 15^f, which impacts the end of the tool T during the operation of the machine. The groove 12^c forms the air-receiving chamber, and the shells 7 and 12 have a communicating threaded bore 2^a to receive the joint 2, to which joint 2 the air-supply pipe 2^b, having a suitable cut-off valve 2^c, is secured. The groove 12^d forms the exhaust-receiving chamber from which the exhaust air passes through 55 apertures 7^x to the atmosphere. The apertures are preferably arranged so as to exhaust against the material worked upon to blow away the chips.

14 designates a cast-steel bushing having a longitudinal bore 14^a and a hexagonal countersunk portion 14^b, and the said bushing is fitted into the casing or shells 7 and 12, as clearly shown in Fig. 2, the drilling-tool T fitting into the hexagonal countersunk portion

14^b and projecting through the bore 14^a to be 65 impacted by the hammer portion 15^f.

The valve 15 reciprocates longitudinally within the inner shell 12 and automatically serves to cut off communication between the various chambers in the inner shell at various times to allow of proper feeding of the working agent to the valve to cause the same to reciprocate in a manner clearly understood from the drawings. The inner end of the shell 12 is closed by a soft metal disk 13, as shown.

75 So far as described the manner in which my invention operates will be best explained as follows:

After the drill is adjusted to operate upon the rock the parts are placed in the position shown in Figs. 1 and 2. As the rock is drilled the operator moves the drilling-machine proper on its longitudinal axis through an arc of ninety degrees to give the proper twist to the drill, and this is done through the medium of the joint 2, which serves 80 as a handle, as before mentioned. As the rock is cut away the drill is fed toward the same by simply turning the handle 11, which causes the drilling mechanism proper to be fed toward the rock and longitudinally through 85 the casing 1, it being understood that in practice the parts are so designed that a longitudinal movement of nine inches or more may be made without the necessity of changing to a longer drill. However, in practice 90 I prefer to change drills at every six inches of the cut, and when it is desired to change the drills it is only necessary to unclamp the cap 4, when the entire drilling mechanism may be withdrawn from the shell or casing 1 95 by simply pulling the same out through the end of greater diameter of the casing 1, it being understood that the joint 2 in this case passes through the longitudinal slot 1^b of the casing 1 from the end of reduced diameter toward the end of greater diameter. As soon as the new drill has been adjusted into the hammer end of the drilling mechanism the 100 same can be again clipped into the casing 1 and the cap 4 applied, it being understood that when this is done the screw 10 is turned to bring the plug 9 close to the cap 4, so that the parts will be in their position of less expansion.

105 From the foregoing it will be seen that I have provided a very simple and easy means 115 whereby the drill mechanism may be removed from the work and from its casing and a new drill replaced and the drilling mechanism again put back in its casing without disturbing the adjustment of the machine as a whole, 120 so that when the new drill is in position the same will be in direct alinement with the hole without the necessity of changing the adjustment of the casing, thus enabling me to cut a 125 hole in a more true and direct line than has heretofore been possible and without the necessity of adjusting the mechanism again into alinement with the hole.

Any suitable hammer-and-valve mechanism may be used in connection with my invention; but I prefer to use the hammer-and-valve mechanism such as is disclosed in the accompanying drawings, as the same is of a very simple and compact construction.

From the foregoing description, taken in connection with accompanying drawings, it is thought the complete construction, operation, and many advantages of my invention will be readily apparent to those skilled in the art to which it appertains, and I desire it understood that slight changes in the detailed construction, arrangement, dimension, and operation of parts may be made without departing from the scope of my invention and the appended claims.

Having thus described my invention, what I claim, and desire to secure by Letters Patent, is—

1. A rock-drilling mechanism comprising a fixedly-held casing and a pneumatic hammer longitudinally adjustable within said casing and telescopically arranged with respect to the casing, means for adjusting said hammer within said casing, means for detachably securing the hammer and hammer-adjusting means within the casing, said hammer and said adjusting means being bodily removable from the casing.

2. A rock-drilling mechanism comprising a casing, a pneumatic hammer held within said casing, means operating with said hammer and casing to move said hammer longitudinally within said casing, said hammer and said hammer-moving means being bodily removable from the casing.

3. In an apparatus of the character stated, a base, a cylindrical casing fixedly secured to said base, a pneumatic hammer mechanism within said casing, a detachably-secured cap for one end of said casing, means within said casing and connected with said hammer mechanism and said cap for moving the hammer mechanism longitudinally within said casing, said hammer mechanism, said hammer-mechanism-moving means and said cap being bodily removable from the casing.

4. A rock-drilling mechanism comprising a plurality of telescopic sections, a pneumatic hammer mechanism carried by one of said sections, and means for extending and contracting said telescopic sections, means for holding one section stationary, and means for detachably connecting said telescopic sections with each other to permit of the inner section being bodily removable from the outer section.

5. In a rock-drilling mechanism, a plurality of telescopic tubular sections, a base to which the outer section is secured, a pneumatic hammer mechanism in the inner section, means connected with the outer and the inner tubular sections for extending and contracting the same, means for detachably securing the inner section and its parts within the casing, said

inner section and its parts being bodily removable from the outer section.

6. In an apparatus of the character stated, a base, a tubular casing fixedly secured thereto, said base and said casing having a longitudinal slot, a detachably-secured closure-cap for one end of said casing, a pneumatic hammer mechanism longitudinally adjustable within said casing, said hammer mechanism comprising a tubular shell and a reciprocating valve having a hammer-head within said tubular shell, a coupling-joint secured to the shell for coupling with the source of fluid-supply to admit the fluid into said shell to operate said valve, said casing and said shell being telescopically arranged and said shell and its carried parts being bodily and endwise removable from the casing, the coupling-joint being slideable through said casing, and base-slots from end to end while the shell is being withdrawn from or entered into the casing substantially as shown and described.

7. In a mechanism of the character stated, a base, a tubular casing secured thereto, said tubular casing and said base having a longitudinal slot extending from end to end thereof, a pneumatic hammer mechanism within said casing and comprising an outer tubular shell telescopically held within said casing, and an inner shell tightly fitted within said outer shell, said inner shell having a plurality of internal grooves forming chambers, a reciprocating valve within said inner shell, said valve having a hammer-head, a drill-receiving bushing held in the outer ends of the outer and inner shells, a closure-disk for the other end of the inner shell, said outer shell having one end internally threaded, a supplemental tubular member having a threaded end for engaging the threaded end of the outer shell to form a continuation thereof, a screw-plug in the opposite end of the supplemental tubular sections, a cap detachably secured to one end of the casing, a screw passing through the cap and the screw-plug for adjusting the hammer mechanism, a coupling-joint secured to the outer shell and communicating with the interior of the inner shell for feeding the working agent into the said inner shell to operate the valve.

8. In a mechanism of the character stated, a base, a tubular casing secured thereto, said tubular casing and said base having a longitudinal slot extending from end to end thereof, a pneumatic hammer mechanism within said casing and comprising an outer tubular shell telescopically held within said casing, and an inner shell tightly fitted within said outer shell, said inner shell having a plurality of internal grooves forming chambers, a reciprocating valve within said inner shell, said valve having a hammer-head, a drill-receiving bushing held in the outer ends of the outer and inner shells, a closure-disk for the other end of the inner shell, said outer shell

having one end internally threaded, a supplemental tubular member having a threaded end for engaging the threaded end of the outer shell to form a continuation thereof, a screw-plug in the opposite end of the supplemental tubular sections, a cap detachably secured to one end of the casing, a screw passing through the cap and the screw-plug for adjusting the hammer mechanism, a coupling-joint screwed 10 to the outer shell and communicating with the interior of the inner shell for feeding the working agent into the said inner shell to operate the valve, a screw-plug for the threaded end of the supplemental tubular section which 15 engages the threaded end of the outer shell to extend said end to tightly fit said outer shell substantially as shown.

9. In a mechanism of the character stated, a base, a tubular casing secured thereto, said 20 tubular casing and said base having a longitudinal slot extending from end to end thereof, a pneumatic hammer mechanism within said casing and comprising an outer tubular shell telescopically held within said casing, 25 and an inner shell tightly fitted within said outer shell having a plurality of internal grooves forming chambers, a reciprocating valve within said inner shell, said valve having a hammer-head, a drill-receiving bushing

held in the outer ends of the outer and inner 30 shells, a closure-disk for the other end of the inner shell, said outer shell having one end internally threaded, a supplemental tubular member having a threaded end for engaging the threaded end of the outer shell to form a 35 continuation thereof, a screw-plug in the opposite end of the supplemental sections, a cap detachably secured to one end of the casing, a screw passing through the cap and the screw-plug for adjusting the hammer mechanism, a 40 coupling-joint secured to the outer shell and communicating with the interior of the inner shell for feeding the working agent into said inner shell to operate the valve, a screw-plug for the threaded end of the supplemental tubular section which engages the threaded end 45 of the outer shell to extend said end to tightly fit said outer shell end, all of the parts within the casing, and the cap, being bodily removable from the casing, the coupling-joint 50 passing through said longitudinal slot in the casing-base from end to end during the removing operation, substantially as shown and for the purposes specified.

GRANT W. SMITH.
